DESIGN FOR A CREAM SEPARATOR SUPPLY TANK

Clifford E. Butler, Waterloo, Iowa

Application July 20, 1945, Serial No. 120,819

Term of patent 14 years

(Cl. D23—1)

To all whom it may concern:

Be it known that I, Clifford E. Butler, a citizen of the United States and a resident of Waterloo, in the county of Blackhawk and State of Iowa, have invented a new, original, and ornamental Design for a Cream Separator Supply Tank, of which the following is a specification, reference being had to the accompanying drawing, forming a part thereof.

Figure 1 is a side elevational view of a cream separator supply tank, showing my new design.

Figure 2 is a top plan view of the same.

Figure 3 is a sectional view taken on the line 3—3 of Figure 2.

Figure 4 is a rear elevation, partly in section, on the line 4—4 of Figure 2.

I claim:

The ornamental design for a cream separator supply tank, substantially as shown.

CLIFFORD E. BUTLER.
